UNITED STATES PATENT OFFICE.

ALBERT F. FISCHER, OF IOWA CITY, IOWA.

ROAD DRAG.

Application filed June 1, 1922. Serial No. 565,078.

To all whom it may concern:

Be it known that I, ALBERT F. FISCHER, of Iowa City, in the county of Johnson and State of Iowa, have invented certain new and useful Improvements in Road Drags; and I do hereby declare the following to be a full, clear, and exact description of the invention, such as will enable others skilled in the art to which it appertains to make 10 and use the same.

This invention relates to an improvement in road machines, and more particularly for scarifying, dragging, distributing loose materials in depressions and the spreading and packing of loose materials on a sand-clay, earth or gravel road, and leaving the finished road with the configuration of a crown, all of which the machine performs in one operation.

20 These several features are accomplished by the employment of a plurality of converging and diverging blades carried by a frame that is drawn over the road surface.

The invention consists of certain novel 25 features of construction and combinations of parts which will be hereinafter described and pointed out in the claims.

In the accompanying drawings, Figure 1 is a top plan view of the invention. Figure 2 is a longitudinal vertical sectional view. Figure 3 is a detail sectional view showing the manner of mounting the crowning blade. Figure 4 is a vertical sectional view showing the manner of adjusting the angle of the 35 crowning blade. Figure 5 is a detail sectional view showing the manner of fastening the cross beams to the runner and the blades to the cross beams. Figure 6 is a detail sectional view showing the manner 40 of attaching the angular blades to the cross beams. Figure 7 is a perspective view of a portion of the scarifier.

The machine is intended to be constructed of metal parts although it is possible to employ other materials, and as shown, the frame is rectangular in shape, consisting of parallel runners 10, 10, and front and rear channel beams 11 and 12 respectively. The front beam 11 is interposed between the forward ends of the runners and supports an adjustable scarifier 13 conforming to the crown of the road, which breaks up the bumps or accumulations which may gather on the travelled roadway.

55 The scarifier 13 is provided with a series of steel teeth 39 concaving forwardly, and

is journaled to the runners by a shaft 40. The lower face of the scarifier is curved to conform to the crown of the road surface. A lever 41 is attached to the scarifier 13, 60 and cooperates with a bar 42 attached to the beam 11, and is provided with holes through which a pin may be inserted for holding the scarifier at various angles according to the use to which it may be employed. 65

Arranged transversely of the frame and at suitable intervals are cross beams 14, 15, 16, 17, preferably T-shaped. These beams are connected to the runners 10 by bolts 18.

Attached to the forward ends of the runners 10 are two blades 19. These blades converge toward each other and are attached at their inner ends by means of bolts to the cross beam 14. The blades do not come together at their inner ends but an opening 20 75 is formed therebetween for the passage of the loose dirt. On the front sides of the blades are wear or scraping plates 21. The blades 19 are inclined so that their lower surfaces are elevated and lie in a higher 80 plane than at their forward ends thereby conforming to the crown of the road bed. Located back of these blades 19 are blades 22 carried by cross beams 15 and 16, to which they are suitably attached. These 85 blades are provided with wear or scraping plates 23. The forward ends of the two blades 22 are brought together while their rear ends extend toward the runners 10. A space 24 is formed between the ends of 90 these blades and the runner to permit the loose earth or dirt to pass off from the blades and around their ends. These blades are supported at their forward ends at an elevation somewhat higher than the elevation 95 of the rear terminals of the blades 19 and gradually slope downwardly toward the runners 10 whereby they conform to the road surface.

Another set of blades 25 are attached at 100 their forward ends to the runners 10 and extend at an angle inwardly toward the rear of the machine. These blades are inclined somewhat similarly to the blades 19 and their inner ends are located at an elevation slightly higher than the inner ends 105 of the blades 19. The inner ends of these blades being supported by the cross beam 17 and are provided with wear or scraping plates 26. An opening 27 is formed between 110 the inner ends of the blades for the discharge of the loose material which has been

collected. It is to be noted that the angle of the blades 19 and 22 are approximately the same with respect to the runners 10 while the angle of the blades 25 is greater and their inner ends are brought closer together and a smaller opening is formed between the ends of these blades than that formed between the ends of the blade 19. A crowning blade 28 extends transversely of the machine and is journalled to the runners 10 by a shaft 29. The lower or working surface of blade 28 is made concave to conform to the contour of the crown or road surface. The crowning blade 28 is capable 15 of an oscillatory movement for changing the angle of the same to meet the requirements and is accomplished by means of a lever 30 attached to the blade. Plate 31 is provided with a plurality of perforations 20 or holes through which a pin may be inserted for holding the lever in various positions of adjustment of the blade 28. The blade 28 is provided with a wear plate 33 which conforms to the shape of the blade.

25 As the machine is drawn along the road surface the scarifier 13 will break up the enlargements or uneven surface and this loose material will be first taken up and acted upon by the blades 19. The blades 30 19 and 22 are scraping and shaving blades and will act upon the road surface causing the roughened surface of the roadway to be shaved or cut and the loose material removed by the scarifier and will 35 pass along the blades and will first be discharged from the blades 19 through the opening 20 formed between the ends of the blade and delivered onto the blades 22. This loose material together with the loose earth 40 removed by the blades 22 will then be delivered onto the blades 25, the loose earth passing from the blades 22 through openings 24 formed between the ends of these blades and the side of the frame. Plates 45 26 extend only a short distance from the forward ends of the blades 25, that is, a short distance beyond the outer ends of the blades 22 so that a scraping action is produced along the sides of the frame inwardly for a short distance. Plates 26 project approximately one half of an inch below the bottom edge of the blades 25 so that these blades or the bottoms thereof do not come in contact with the road surface and as the 55 material which has been delivered to the blades 25 is fed or carried along these blades due to the movement of the machine the loose earth will pass beneath the blades 25 and enter the holes or depressions in the 60 road surface and be packed therein. The remaining loose earth which does not pass beneath the blades 25 will pass through opening 27 formed between the ends of these blades and will be delivered to the crowning blade 28. The crowning blade 28 may

be adjusted or tilted forward sufficiently to allow the passage of just enough loose material to give the proper crown finish to the road bed and to properly pack the loose material. By referring to Figure 2 it will 70 be noted that wedges or blocks 34 are inserted between the runners 10 and the cross beams 14, 15, 16 and 17 whereby these beams may be elevated to the proper height to support the various blades. This adjustment 75 permits the inner ends of the blades 19 to be elevated to conform to the crown of the road and the same is true of the blades 22 while the adjustment for the blades 25 insures that they will conform to the road 80 surface yet their lower surfaces are elevated approximately one half of an inch above the bottoms of the blades 19 and 22 so that they will be sufficiently elevated to come above the loose material and cause 85 it to be packed into the holes or depressions of the road surface.

Connected to the forward ends of the runners 10 are straps 35 and connected to these straps are pull bars 36 by means of rings 37. The ends of the pull bars are adapted to be connected to the draw bar of a tractor by chains or the like for pulling the road machine along the roadway.

I claim as my invention:

1. A road drag including a frame having a pair of spaced parallel runners adapted for gaging the width of a roadway, a pair of scraping blades mounted on the forward portion of the frame with outer ends engaging the runners and converging rearwardly leaving a space between the inner ends for the passage of material scraped thereby, a second pair of blades mounted on the frame in the rear of the first mentioned blades, and having their forward ends secured together and positioned in line with the space between the first pair of blades and inclined outwardly and rearwardly toward the runners but having the outer ends spaced therefrom for distributing material from the scraping blades, a third pair of blades mounted on the frame having the outer ends engaging the runners and inclined inwardly and rearwardly and having the free ends in spaced relation for returning material from the second pair of blades or distributing blades to the center portion, and an adjustable crowning blade for finishing and crowning the entire road surface.

2. A road drag including a frame having a pair of spaced parallel runners adapted for gaging the width of a roadway, scraping blades mounted at the forward end of said frame for scraping the roadway between said runners and depositing the material scraped in the center portion of the roadway, distributing blades mounted in the rear of said scraping blades and adapted for distributing the material from said scraping

blades over the surface of said roadway, returning blades mounted in the rear of said distributing blades for receiving surplus material from said distributing blades and 5 returning it to the center portion of the roadway, a crowning blade pivotally mounted in the rear of said frame and said returning blades for crowning and finishing said roadway, a lever mounted on said crowning

blade, a bar mounted on said frame and 10 means for securing the lever in any one of a plurality of predetermined positions on said bar for positioning the crowning blade in a desired position of adjustment relative to said frame.

In testimony whereof I have signed this specification.

ALBERT F. FISCHER.
